GOLF CLUB HOLDER AND CART

James L. Herold, 8467 Roanoke Drive, Normandy, Mo.
Filed Mar. 16, 1959, Ser. No. 799,616
10 Claims. (Cl. 280—47.19)

This invention relates to golf club holders, and more particularly to an improved golf club holder of the type in which a separate compartment is provided for each golf club and to an improved golf cart in which such a holder is associated with a wheeled support.

Among the several objects of the invention may be noted the provision of an improved golf club holder in which the number of separate compartments provided for holding individual golf clubs may be readily varied depending upon the number of golf clubs to be carried by the user; the provision of a golf club holder of this type in which a damaged compartment may be readily removed and replaced; the provision of such a golf club holder in which each separate compartment is provided with a drain opening at the bottom thereof to permit the draining of water; the provision of a golf club holder of the class described which is of simple and economical construction; and the provision of an improved golf club cart including such a golf club holder in association with a wheeled support, which cart is provided with means constituting a stand for the cart when the latter is in a generally vertical position and a seat for the user when the cart is in a generally horizontal position. An adjustable handle is provided in association with the improved golf cart and is not required when the golf club holder is used with an existing conventional cart. Other objects and features will be in part apparent and in part pointed out hereinafter.

The invention accordingly comprises the constructions hereinafter described, the scope of the invention being indicated in the following claims.

In the accompanying drawings, in which several of various possible embodiments of the invention are illustrated,

FIG. 1 is a side elevation of a golf club cart of the invention, with parts broken away and shown in section;

FIG. 2 is an enlarged top plan view taken on line 2—2 of FIG. 1;

FIG. 3 is a fragmentary vertical cross section taken on line 3—3 of FIG. 2;

FIG. 4 is a horizontal cross section taken on line 4—4 of FIG. 1 with parts broken away;

FIG. 5 is a fragmentary vertical cross section taken on line 5—5 of FIG. 4;

FIG. 6 is a view similar to FIG. 4 showing a modification;

FIG. 7 is an enlarged vertical section taken on line 7—7 of FIG. 6;

FIG. 8 is a view in elevation showing a brace used in conjunction with the modification of FIGS 6 and 7; and,

FIG. 9 is a view similar to FIG. 4 showing another modification.

Corresponding reference characters indicate corresponding parts throughout the several views of the drawings.

Referring to the drawings, FIG. 1 shows a golf club cart of the invention generally designated 1 comprising a golf club holder generally designated 3 and a wheeled support generally designated 5. Golf club holder 3 comprises a plurality of elongate tubes 7 (nine such tubes being shown), a head member 9 and a base member 11. The upper end portions of tubes 7 are received in head member 9 and lower end portions of tubes 7 are received in base member 11. Tubes 7 may be made of any suitable rigid plastic material. As shown, they are

2

of circular cross section, but this is not essential. The upper ends of the tubes are flared as indicated at 7a.

As shown, head member 9 is generally rectangular in shape and comprises end sections 13 and 15 and intermediate sections 17 and 18. Head member 9 may be made of any suitable material such as wood, plastic or metal such as aluminum. End sections 13 and 15 of head member 9 have a plurality of semicircular notches 13n and 15n on the inner side thereof. Intermediate sections 17 and 18 have a plurality of notches 17n and 18n on each side thereof which correspond to and register with the notches of end sections 13 and 15 and the adjacent intermediate section respectively to form circular openings 19 receiving the upper end portions of plastic tubes 7. End sections 13 and 15 and intermediate sections 17 and 18 are detachably fastened together and the upper ends of the tubes are clamped therebetween by means of bolts 21 extending through registering bolt holes 22 in the end and intermediate sections between the openings 19, nuts 23 and wing nuts 25 being threaded on the ends of the bolts. Vertical holes 27 are provided in the sections of head member 9 providing sockets for receiving golf tees.

Base member 11 is generally rectangular in shape and comprises end sections 28 and 29 (similar to end sections 13 and 15 of head member 9) and intermediate sections 31 and 32 (similar to sections 17 and 18 of head member 9). End sections 28 and 29 have a plurality of semicircular notches 28n and 29n on the inner side thereof. Intermediate sections 31 and 32 have a plurality of semicircular notches 31n and 32n on each side thereof which correspond to and register with the notches of end sections 28 and 29 and the adjacent intermediate section respectively to form circular openings 33 receiving the lower end portions of plastic tubes 7. End sections 28 and 29 and intermediate sections 31 and 32 are detachably fastened together and the lower ends of the tubes are clamped therebetween by means of bolts 35 extending through registering bolt holes 36 in the end and intermediate sections between the openings 33, nuts 37 and wing nuts 39 being threaded on the ends of the bolts. Rods or wires 41 extend through the lower end portions of tubes 7 just above the base member 11. As shown, rods 41 partially close the bottom of tubes 7 and provide a bottom stop for golf clubs inserted in the tubes. The spaces on either side of rods 41 provides drain openings for water to drain out of tubes 7. Openings 43 are provided in end section 28 of base member 11 for a purpose to be described, and openings 43a may be provided in the other sections of the base member for holding tees.

As shown, golf club holder 3 has nine separate compartments for holding nine golf clubs constituted by the nine individual plastic tubes 7. If it is desired to provide additional compartments for additional golf clubs such as, for example, three or six additional clubs, end sections 13 and 15 and intermediate sections 17 and 18 of head member 9 and end sections 28 and 29 and intermediate sections 31 and 32 of base member 11 may be unfastened or detached from each other by removing bolts 21 and 35 respectively. Additional intermediate sections may then be inserted between or adjacent intermediate sections 17 and 18 and 31 and 32 of head member 9 and base member 11 respectively, and these members may then be fastened together by bolts similar to bolts 21 and 35 but of suitable greater length. Each additional intermediate section added to each of head and base members 9 and 11 provides three additional openings for receiving three individual plastic tubes for holding three golf clubs. Similarly, where one or more of tubes 9 have been damaged, the damaged tubes can be replaced

by disassembling head and base members 9 and 11 as described above, removing the damaged tubes, inserting new tubes and thereafter refastening head and base members 9 and 11 as before.

An angle bar 45 is secured to the end section 13 of head member 9 with one leg overlying the top and the other extending downward and engaging the outside of the end section 13. Securement is effected by means of the bolts 21 extending through holes in the downwardly extending leg and by the wing nuts 25. An angle bar 47 is secured to the end section 15 of head member 9 with one leg overlying the top and the other extending downward and engaging the outside of end section 15. Securement is effected by means of the bolts 21 extending through holes in the downwardly extending leg by the nuts 23. The downwardly extending leg of angle bar 45 is provided with outwardly extending flanges 49 at its ends. These flanges have openings 51 pivotally receiving inturned end portions 53 of a bail type handle 55. The upper leg of angle bar 47 has upwardly extending flanges 57 at its end having laterally outwardly projecting wings 59 each formed with a series of notches 61. The side arms 62 of the handle are springingly receivable in a pair of the notches 61. A handle grip 63 is provided on the outer end portion of the handle, and the handle may be adjusted to various angles for adjustment of the elevation of the handle grip by springing side arms 62 into different pairs of notches.

Wheeled support 5 comprises an axle member 65 having wheels 67 journaled at the ends thereof. A pair of spaced angle bars 69 extends from the axle member 65 at right angles thereto. These have bent up inner end portions 71 fastened to the axle member as indicated at 73. For reinforcing the angle bars 69, gusset plates 75 are fastened to bars 69 as indicated at 77. Angle bars 69 are arranged with one leg thereof vertical and their other legs extending inward toward one another at the bottoms of the vertical legs. On the inner side of angle bars 69 are a pair of spaced inverted angle bars designated 79. These are fastened to bars 69 and gusset plates 75 as indicated at 81. Upper legs 83 of bars 79 and lower legs 85 of bars 69 form channels for removably receiving the base member 11 of golf club holder 3. Upper legs 83 of bars 79 have notches 87 therein at the inner end thereof with which the openings 43 in base member 11 register when the base member 11 is slid into the stated channels provided by bars 69 and 79. A chain 89 having a pin 91 at one end thereof is fastened to axle member 65 at the other end thereof as indicated at 93. After sliding the base member 11 of golf club holder 3 into the channels formed by bars 69 and 79, holder 3 is locked in position by inserting pin 91 into openings 43 through notches 87.

A channel member 95 is fastened to the outer ends of angle bars 69 on the bottom side thereof as indicated at 97. As shown in FIG. 1, channel member 95 serves as a stand to hold the golf club holder 3 in an upright position. The assembly may be turned clockwise from its FIG. 1 position to a generally horizontal position in which channel member 95 may be utilized as a seat.

A sheet 101 of hardboard (such as that sold under the trade designation "Masonite") or the like and a metal plate 103 may be fastened to the row of plastic tubes 7 away from the wheels 67 as indicated at 105. Metal plate 103 has an opening 107. A carrying strap 109 has one end secured in opening 107 in the plate 103 and its other end secured in an opening 111 in bar 45. The lower end of board 101 and a metal plate 115 are fastened to the lower ends of the outer row of tubes 7 as indicated at 117. A pouch 119 for holding golf balls rests against board 101 and is secured at its end between metal plates 103 and 115 respectively and board 101 at 105 and 117 respectively. The pouch may have an opening in the outside thereof with a slide fastener.

It will be understood that golf club holder 3 may be

used alone or in association with wheeled support 5 as a cart as shown. Also, handle 55 on head member 9 of golf club holder 3 eliminates the necessity for any upright supporting member on the wheeled support, plastic tubes 7 making the structure sufficiently rigid without any such supporting member.

FIGS. 6 and 7 illustrate a modification wherein, instead of using rods 41 to provide bottom stops for the clubs, the sections 28, 29, 31 and 32 of the base member 11 are formed with inwardly directed flange portions 28f, 29f, 31f and 32f at the lower ends of the notches 28n, 29n, 31n and 32n. When the sections 28, 29, 31 and 32 are assembled, these flange portions provide upwardly facing shoulders such as indicated at 121 in FIG. 7 engageable by the lower ends of the tubes 7. The flange portions are formed so as to provide a drainage hole 123 for water to drain out of each tube 7. Each tube 7 has a ring 125 of rubber or other suitable resilient material inserted therein at its lower end engaging the respective shoulder 121 providing a resilient stop for a golf club inserted in the tube. When the modification of FIGS. 6 and 7 is used, it is preferred to tie together the base member 11 and the head member 9 as by means of a tie member such as indicated at 127 in FIG. 8 to keep the tubes 7 from sliding out of the recesses provided for the lower ends thereof by the notches 28n, 29n, 31n, 32n. As shown in FIG. 8, the tie member 127 comprises a rod having a forked upper end 129 secured to the head member 9 by engagement with the ends of the bolts 21 under the nuts 23 on the bolts 21 and a forked lower end 131 secured to the base member 11 by engagement with the ends of bolts 35 under the nuts 39 on the bolts 35.

FIG. 9 illustrates a further modification wherein the bolts 35 are utilized as bottom stops for the golf clubs, 35 extending across the tubes 7 adjacent the lower ends of the tubes 7 (instead of intermediate the lower ends of the tubes as in FIG. 4). In this instance, holes such as indicated at 141 are provided in the tubes 7 for accepting the bolts 35. Sleeves 143 of rubber or other suitable 40 resilient material may be provided on the portions of the bolts which span tubes 7 to provide resilient stops for the ends of the golf clubs.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. A golf club holder comprising a rectangular base member and a rectangular head member, each of said members comprising two end sections and at least one intermediate section located between said end sections, each of said end sections having a plurality of notches on the inner sides thereof, each of said intermediate sections having a plurality of notches on each side thereof corresponding to and registering with the notches of the respective end sections and any adjacent intermediate section to form rows of openings in said base member and said head member with each opening in the base member coaxial with a respective opening in the head member, a plurality of rigid tubes each having its lower end received in one of the said openings in the base member and extending upward therefrom through the coaxial opening in the head member, the upper end portions of said tubes projecting upward above said head member and being flared, means for detachably securing together the end and intermediate sections of the base member and clamping the lower ends of the tubes between the end and intermediate sections of the base member, means for detachably securing together the end and intermediate sections of the head member and clamping the upper end portions of the tubes between the end and intermediate sections of the head member.

ate sections of the head member, said rigid tubes as clamped in said base and head members serving as structural members holding said base and head members in spaced relation at the lower and upper ends of the holder, and means in the lower ends of the tubes for supporting the ends of golf clubs inserted in the tubes.

2. A golf club holder as set forth in claim 1 wherein the sections of the base member and the sections of the head member are detachably fastened together by means of bolts extending through each member from one end section to the other between the tube-receiving openings therein.

3. A golf club holder as set forth in claim 2 wherein the means in the lower ends of the tubes for supporting the clubs comprises rods extending through the tubes crosswise in relation to the bolts.

4. A golf club holder as set forth in claim 2 wherein the means at the lower ends of the tubes for supporting the clubs comprises inwardly directed flange portions at the lower ends of the notches in the sections of said base member providing shoulders engageable by the lower ends of the tubes, said flange portions being formed to provide drainage holes for draining water from the tubes, and resilient rings in the lower ends of the tubes engaging said shoulders.

5. A golf club holder as set forth in claim 1 wherein the sections of the base member are detachably fastened together by means of bolts extending through said base member from one end section thereof to the other and through said tubes, and wherein the means in the lower ends of the tubes for supporting the clubs includes resilient sleeves on the portions of the bolts spanning the tubes.

6. A golf club holder as set forth in claim 1 which is adapted for mounting on a wheeled support and has a handle pivoted on said head member and means on said head member engageable by said handle to hold it in different positions of angular adjustment relative to said head member.

7. A golf club cart comprising a two-wheeled support and a golf club holder, said holder comprising a rectangular base member and a rectangular head member, each of said members comprising two end sections and at least one intermediate section located between said end sections, each of said end sections having a plurality of notches on the inner sides thereof, each of said intermediate sections having a plurality of notches on each side thereof corresponding to and registering with the notches of the respective end sections and any adjacent intermediate section to form rows of openings in said base member and said head member with each opening in the base member coaxial with a respective opening in the head member, a plurality of rigid tubes each having its lower end received in one of the said openings in the base member and extending upward therefrom through the coaxial opening in the head member, means for de-

tachably securing together the end and intermediate sections of the base member and clamping the lower ends of the tubes between the end and intermediate sections of the base member, means for detachably securing together the end and intermediate sections of the head member and clamping the upper end portions of the tubes between the end and intermediate sections of the head member, said rigid tubes as clamped in said base and head members serving as structural members holding said base and head members in spaced relation at the lower and upper ends of the holder, means in the lower ends of the tubes for supporting the end of golf clubs inserted in the tubes, said two-wheeled support comprising an axle member having wheels at the ends thereof and a pair of channels extending from the axle member at right angles thereto, the open sides of said channels being opposed to one another, said base member having opposite sides thereof slidably received in said channels and being removable therefrom, means for retaining said base member in said channels, and said head member having a handle thereon for pulling the cart.

8. A golf club cart as set forth in claim 7 wherein the means for retaining said base member in said channels comprises means carried by the support for locking the base member in said channels.

9. A golf club cart as set forth in claim 8 wherein said base member and said channels have registering openings and said support carries a pin on a chain receivable in said openings for locking the base member in said channels.

10. A golf club cart as set forth in claim 7 wherein means is secured to the outer ends of said channels providing a stand for the cart when the cart is in a generally vertical position and a seat when the cart is in a generally horizontal position.
